UNITED STATES PATENT OFFICE.

JOHN CLEMENT ABELL, OF LEBANON, KENTUCKY.

DESIGN FOR A MANTEL.

SPECIFICATION forming part of Design No. 21,162, dated November 10, 1891.

Application filed October 13, 1891. Serial No. 408,615. Term of patent 14 years.

To all whom it may concern:

Be it known that I, JOHN CLEMENT ABELL, a citizen of the United States, residing at Lebanon, in the county of Marion and State 5 of Kentucky, have invented a new and original Design for Mantels, of which the following is a specification.

The invention relates to a new and original design for mantel-pieces.

10 The object of the present invention is to provide an ornamental and attractive mantel-piece.

15 The essential feature of the invention resides in the particular ornamentation of the face of the mantel-piece, and consists of flowers and leaves arranged in the form of a vine and disposed on a roughened surface.

20 In the drawing the figure is a front elevation of a mantel-piece, showing the original design.

Like numerals of reference indicate like parts in all the figures of the drawing.

1 designates a mantel-piece consisting of a horizontal portion 2 and vertical portions 3, 25 which have their edges beveled at intervals. The face of the mantel-piece is ornamented by raised leaves 4 and flowers 5, arranged in the form of a vine and disposed on a roughened or broken surface 6. The horizontal 30 portion of the mantel-piece is provided at the ends and at the middle with three rows of vines arranged parallel and vertically, and

the rows at the ends are separated from those at the middle by horizontally-disposed vines. The vertical portions of the mantel-piece are 35 each ornamented by a vertical vine extending from the top to near the bottom and by a horizontal vine arranged a short distance below the end of the vertical one.

The shelf, face, and legs are neatly beveled 40 on the edges and ends at intervals, which bevels will in practice be painted in a different but suitable color to the body of the mantel. The ornamental portions of the mantel are composed of plaster-of-paris beautifully 45 stamped in flowers, leaves, and other designs that are attached or placed on the surface in a diversity of ways, thereby making them very neat, beautiful, and attractive.

The face of the mantel is designed in practice 50 to be highly polished and painted in different corresponding colors, so as to harmonize with the colors of the ornamental and beveled portions of the mantel.

What I claim is—

55 The design for mantel-pieces herein shown and described.

In testimony that I claim the foregoing as my own I have hereto affixed my signature in the presence of two witnesses.

JOHN CLEMENT ABELL.
